UNITED STATES PATENT OFFICE.

HAROLD LEE DAVIDSON, OF LOUISVILLE, KENTUCKY, ASSIGNOR OF ONE-HALF TO JOHN C. DAVIDSON, OF LOUISVILLE, KENTUCKY.

COPYING-PRESS.

SPECIFICATION forming part of Letters Patent No. 719,759, dated February 3, 1903.

Application filed March 3, 1902. Serial No. 96,507. (No model.)

To all whom it may concern:

Be it known that I, HAROLD LEE DAVIDSON, a citizen of the United States, residing at Louisville, in the county of Jefferson and State of Kentucky, have invented an Improved Copying-Press, of which the following is a specification.

My invention relates to that class of copying-presses in which rollers are used; and the objects of my improvement are to provide a press which shall be simple in construction, effective in use, doing its work rapidly in copying on detached sheets or on a continuous strip or in a book, and which may be produced at small cost.

The details of construction, arrangement, and operation are as hereinafter described, reference being had to accompanying drawings, in which—

20 Figure 1 is a perspective view of the press secured to a bench or table, as in use. Fig. 2 is a face view of the upper portion of the press, the hinged portion of the frame which carries the pressure-roller being thrown back.

25 Fig. 3 is a detail side view of the upper portion of the press, showing the attachment and arrangement of the compression-clamp. Fig. 4 is a detail section illustrating the application of the endless moistening-belt to the

30 driving-roller. Fig. 5 is a perspective view illustrating the construction and arrangement of the paper-guard employed for separating wet sheets of the copying-paper from the belt. Fig. 6 is a plan view of the press,

35 including a portion of the table to which it is attached and a portion of a copying-book placed in position on the table. Fig. 7 is a side or edge view of the press, showing it attached to the edge of a table. Fig. 8 is a 40 vertical section of the press, the copying-book, and the table upon which the latter rests.

As indicated particularly in Fig. 1, the letter A indicates the main portion of the frame of the press, which is provided with screw-clamps 1, adapted to be applied to the edge of a bench or table 2 and to support the press in vertical position, as shown in Fig. 1.

45 B indicates the upper portion of the frame, which is hinged at 3 to a stationary portion A and is thus adapted to be thrown back

and rest in vertical position, as shown in Fig. 2. A driving-roller 4 is journaled in the upper portion of the stationary part A, and a moistening-belt C runs thereon, as shown. 55 An idler-roller 5 is arranged in the lower portion of the belt within a water-trough D, which forms an attachment of the vertical legs 6 of frame A. The reduced ends of the idler 5 form journals which work in grooves 7, formed 60 longitudinally in the frame-legs 6. The said roller is therefore adapted for free vertical movement. In practice it rests in and is supported by the belt C alone, and its weight serves to hold the latter stretched duly taut. 65 The rollers 3 4 5 are covered with rubber to form an elastic working surface. As shown in Fig. 4, the edges 8 of the belt C are thickened or enlarged, and thereby rendered stronger than the intervening portion of the belt. Further, the belt is made of slightly greater width than the length of the said roller 4, so that the thickened portion 8 runs contiguous to the ends of the roller, as shown. By this means the belt is kept securely in place on 70 the roller without the aid of extraneous guides or other devices for the purpose. For the purpose of detachably connecting the trough D with the pendent frame-legs 6 I employ spring-catches 9, whose free upper ends are 75 bent laterally and adapted to enter holes formed in the said legs. It is obvious that this attachment provides for vertical adjustment of the trough D as conditions may require. The trough is provided at its ends 80 with vertical flange-guides 10, which receive the channel-legs 6 of the frame A and hold the trough D in due vertical and central position whatever be its vertical adjustment. The said legs 6 are preferably formed of sheet 85 metal or channel-iron and securely riveted to the upper portion of the frame A, which is preferably constructed of cast-iron. As shown in Fig. 1, the upper portion of the frame is suitably constructed to form bearings for the journals of the driving-roller 4. 90 The right-hand journal 4^a of said roller is provided with a crank 11, which is clamped thereon by means of a screw. In the hinged portion B of the frame is journaled the upper 95 or pressure roller 4^b, the journals of the same having their bearings in boxes 12, and the

arrangement being such that when the hinged frame B is closed down upon the main frame A, as shown in Figs. 1, 3, and 7, the upper roller presses upon the lower one, or rather upon the belt carried thereby. For the purpose of adjusting the pressure of the upper roller upon the lower as may be required I employ screws 13, which work in threaded bores formed vertically in the end portions 10 of the hinged frame B. The lower ends of these screws are so constructed as to adapt them to slide into undercut or T shape grooves (see Figs. 1 and 7) which are formed in the upper sides of the bearings 12. This 15 construction permits the bearings 12 to be inserted endwise in boxes formed at the ends of the hinged frame B. For the purpose of locking the bearing-blocks 12 of the frame B and yet permit them to have vertical movement, as required for vertical adjustment of the pressure-roller 4^b, I employ screws 14, which are inserted horizontally through the dogs formed at the ends of the hinged frame B and whose points enter vertical grooves in 20 the blocks 12. The heads of the adjusting-screws 13 may be enlarged, or they may be provided with sockets for adjustment of a suitable wrench for turning.

For the purpose of securing the hinged frame B, with its rollers 4^b, to the main frame A in working position I employ what I term a "compression-clamp" E. The same is constructed practically upon the principle of a toggle-lever. Hook-levers 15 are pivoted in 35 parallel position at 16 on opposite sides of the right-hand journal-box of frame B, and their upper ends are pivoted to a lever 17, whose lower end is forked and pivoted at a point above the fulcrum of the hook-levers. 40 The said lever 17 is provided with a handle 17^a, which extends at right angles to it inward, and when the clamp E is closed, as shown in Figs. 1 and 6, such handle lies in horizontal position directly upon the frame 45 B. It will be further seen that in such position the hook-levers 15 are nearly in vertical alignment with the lever 17. The hinged lower ends of said levers engage lugs 18, which project laterally from the frame A, and when 50 the handle-lever 17 is thrown to the position shown in Fig. 1 the hooks engage lugs 18, and thus the frame B is locked in position and the upper roller 4^b is pressed hard upon the driving-roller 4. To permit the required 55 movement of the hook-levers 15, they are provided with diagonal slots at the fulcrum-point. In other words, the guide-screws 16 pass through inclined slots which allow a certain required movement of the levers 15, whereby 60 they are adapted to engage with and to be disengaged from the lugs 18 when the handle-lever 17 is suitably manipulated for the purpose. It will be understood that the pivotal connections are such that when the handle-lever 17 is thrown to the closed position, 65 Fig. 1, the upper ends of the hook-levers 15 are thrown slightly back or to the left of a

vertical line drawn through their pivot and the lugs 18 and the fulcrum of the handle-lever 17. Thus the compression-clamp E is 70 self-locking.

A skeleton paper or letter rack F is provided in front of the rollers 4 4^b. (See Figs. 1, 6, and 8.) The same comprises horizontal rods 19, which are curved downward at their 75 outer ends and connected with a curved rod 20, the whole being arranged horizontally, whereby it is adapted to support a letter or other paper requiring to be copied. This 80 frame 19 20 forms a rigid attachment by means of a horizontal angle-bar 21, whose inner end is riveted to a lug or projecting portion of the frame B at a point adjacent to its hinge. Other rods or fingers 19^a are arranged over the rods 19 and separated therefrom, as shown, 85 to allow convenient insertion of a letter or other paper. These upper rods 19^a form also a fixed attachment of the angle-bar 21. In Fig. 2 this rack F is shown thrown up, together with the swinging frame B and the 90 pressure-roller 4^b. A copying-book G is shown resting upon the table 2, and this may be of such width as to nearly fill the space between the upper portion of the screw-clamps 1, as shown in Fig. 6, so that such clamps 95 form guides serving to hold the book in due position as to lateral movement.

The upper portion B of the frame, with its roller 4^b, must be swung up out of the way for each copy that is made, so that the sheet of 100 copying-paper may be laid over or upon the belt C, whereupon the frame B is thrown down to its normal working position and the compression-clamp E is manipulated to lock it securely in place. It is apparent that this 105 operation requires but a single motion of the operator—that is to say, a single manipulation of the toggle-lever 17.

For the purpose of driving upward the letter which is copied I employ a deflector 22, the same consisting of a metal plate arranged horizontally in front of the rollers 4 4^b (see 110 Fig. 8) and the same being pivoted in the brackets 23, attached to the frame B. The form of this deflector is an oblong rectangle. 115 The book or assemblage of copying leaves or sheets rests upon the shelf or support 2, (see Fig. 8,) the sheets being turned back from their connected edges, which lie opposite the fundamental roller 4, but separated therefrom 120 by a space sufficient to allow a leaf or sheet to follow the moistening-belt downward and strip off therefrom. When the copying-sheet is drawn directly across from the book G to the rollers, as shown by dotted lines in Fig. 125 8, the swinging or free edge of the deflector 22 rests by gravity upon it and swings with it when it moves downward. The advancing edge of the letter or other paper being copied strikes the deflector and is directed upward 130 by it, being thus separated from the wet copying-sheet.

It will be understood that to begin the copying operation the upper portion B of the frame

is swung up into the vertical position shown in Fig. 2, and the copying-sheet from the book G is drawn over and laid upon the belt C. The letter or other writing to be copied is then dropped into the rack F while still held in vertical position, the letter passing thus between the wire rods 19 and 19^a, the letter-head being left in such position that it projects under the roller 4^b. Then the frame part B is closed down, whereby the letter-head is clamped between the two rollers and the compression-clamp E is locked. The crank 11 is then rotated to the right and the letter travels between the rollers and drops down, being gradually separated from the belt C and finally hanging vertical and free, as indicated at 24^a, same figure. This completes the copying operation. The compression-clamp E is then unlocked and the operation repeated.

When sheets bearing copies accumulate, they may be carried back into the position indicated at 24^a by means of a device 25, which is in the nature of a crank. It is fully shown in Fig. 5, the same consisting of a rod bent to suitable form and provided with a crank - handle and journaled in horizontal bars or arms 26, attached to the channel-legs 6 of the main frame A. It will be seen that in operation the crank is swung downward, so as to pass under the set of leaves 24 and come in contact with their upper sides as it swings upward, so as to push them outward when the circle of rotation is completed. It will be understood that the rollers 4 4^b have a suitable elastic covering of india-rubber. It will be understand that my device is especially adapted to permit the copying into the bound or other books, as well as on individual sheets.

What I claim is—

1. In a copying-press, the combination of a frame, comprising a pendent part provided with screw-clamps for adjustment to a table or similar support, a swinging part hinged above the said stationary part and adapted to move in the same vertical plane therewith, a compression-clamp applied on the side opposite the hinge, a fundamental or fixed roller journaled in the upper portion of the said stationary part, a pressure-roller journaled in said swinging part and adapted to lie above and press upon the fixed roller when the hinged frame is closed and locked, and an idler-roller arranged in the lower part of the stationary frame, substantially as described.

2. In a copying-machine, the combination of a frame divided into two parts, a stationary vertical part which carries a driving-roller above and an idler below, and a swinging part which carries a pressure-roller adapted to be brought down upon the drive-roller, and a compression-clamp arranged at the free end of the swinging part and adapted to lock it to the fixed part so as to produce due pressure between the drive and pressure rollers, substantially as shown and described.

3. In a copying-machine, the combination of a series of rollers, a frame, and screw-clamps on said frame for attaching to a table or stand, said screw-clamps forming guides between which a copying-book is placed on said table or stand, substantially as specified.

4. In a copying-press, the combination of a compression-clamp, consisting of tension-plates, a toggle-piece, handle, and lugs, the said tension-plates being provided with slots substantially as shown and described.

5. In a copying-press, the combination of a frame, a train of rollers, and a pivoted swingng deflector for deflecting the letter-sheet, substantially as specified.

6. In a copying-press, the combination of a frame, a train of rollers, and a double crank-guard revolubly mounted in brackets for holding back copied pages of the letter-book, substantially as specified.

7. In a copying-machine, the following combination: a frame comprising a lower stationary part provided with screw-clamps for attaching to a table or stand, an upper part hinged to said lower part on one side and provided with a compression-clamp on the opposite side, a fundamental roller journaled in said stationary part of the frame, an idler-roller at some distance below said fundamental roller, an absorbent moistening-belt working over said fundamental roller and said idler-roller, an adjustable pressure - roller journaled in said upper part of the frame, a letter-feed rack rigidly attached to the said upper part of the frame and swinging therewith, a pivoted letter-deflector mounted on said upper part of the frame and swinging therewith, and a copy-sheet guard mounted on the said lower part of the frame, all adapted, and so coacting as to copy letters rapidly and clearly in a book of copying-paper mounted on the aforementioned table or stand between aforesaid screw-clamps, substantially as and for the purposes specified.

8. In a copying-press, the combination with a stationary frame, of a swinging part which is hinged thereto, and adapted to swing in the vertical plane of said stationary frame, a driving-roller journaled in the upper portion of such stationary part, and adapted to be driven, a pressure-roller journaled in the swinging part, and means for locking the two parts of the frame together detachably and producing pressure between the rollers when the rollers are in horizontal position, substantially as shown and described.

9. In a copying-press, the combination with the main frame provided with screw-clamps for adjustment to a fixed support, a swinging part hinged to the stationary one, rollers journaled in the respective parts of the frame, and a toggle-lever and locking mechanism consisting of a pivoted hand-lever and pivoted hook-levers pivoted together and at different points upon the swinging part and lugs formed on the fixed part with which the hook-levers

are adapted to engage, when the hand-lever is thrown to due position, as shown and described.

10. The combination with a main frame, 5 and rollers journaled and arranged parallel and to work in contact, of a letter-deflector consisting of a plate pivoted adjacent to the rollers, as shown and described.

11. In a copying-press, the combination 10 with a main frame, and a roller arranged in its upper portion, a frame part or section hinged to such main frame, and a roller carried by the hinged frame of a letter-holding rack for supporting letters to be copied, the 15 same comprising upper and lower portions arranged one over the other, and separated at the outer or free edges, the upper portion preventing the letter from toppling off when the upper hinged part of the frame is raised and 20 the angle or separation serving to aline the letter when it is dropped in, as shown and described.

12. The combination of the following means 25 or instrumentalities for effecting copying in the manner described: a guide-frame held in vertical position, a fundamental roller, an idle roller, and a moistening-belt running thereon, a movable frame-section hinged to the top of said guide-frame and a pressure-

30 roller journaled therein, a means for holding the pressure-roller down upon the fundamental one, a horizontal support arranged in proximity to the pressure and fundamental rollers but separated therefrom by a narrow 35 space, a series of copying-sheet sections and held upon the said support with edge of fold adjacent to the fundamental roller, the sections being thrown upward and backward and thus lying horizontal, whereby a section being thrown forward and then passing through 40 the press proper is automatically carried down in the space before referred to, and stripped off the moistening-belt, and hangs suspended vertically, as shown and described.

13. The copying-press adapted for copying 45 into a book and provided with a main section having a roller, and a hinge-section having a roller opposing the main section and arranged to open to permit the insertion between the said rollers of the leaf or leaves of a book and 50 having adjacent to said rollers a device 25 by which to shift the leaves as they accumulate in the operation of making the copies, substantially as set forth.

HAROLD LEE DAVIDSON.
